UNITED STATES PATENT OFFICE.

JOHN C. BARBER, OF CHICAGO, ILLINOIS, ASSIGNOR TO STANDARD CAR TRUCK COMPANY, OF CHICAGO, ILLINOIS, A CORPORATION OF NEW JERSEY.

CAR-TRUCK.

1,094,513.

Specification of Letters Patent. Patented Apr. 23, 1914.

Application filed April 12, 1913. Serial No. 769,613.

To all whom it may concern:

Be it known that I, JOHN C. BARBER, a citizen of the United States, residing at Chicago, in the county of Cook and State of Illinois, have invented certain new and useful Improvements in Car-Trucks; and I do hereby declare the following to be a full, clear, and exact description of the invention, such as will enable others skilled in the art to which it appertains to make and use the same.

My present invention relates to car trucks and particularly to trucks having bolsters mounted for both vertical and endwise movements in respect to the truck side frames, and the invention is directed to the provision, in an extremely simple and efficient manner, of increased wearing face or surface between the bolster and columns of the side frames.

The invention also involves other novel features, all of which will be hereinafter described and defined in the claims.

In the accompanying drawings which illustrate my invention, like characters indicate like parts throughout the several views.

Referring to the drawings, Figure 1 is a view in side elevation with some parts broken away, showing the frame and bolster of a car truck embodying my invention; Fig. 2 is a vertical section taken approximately on the line $a^2 a^2$ on Fig. 1, some parts being broken away; Fig. 3 is a plan view showing a portion of one truck side frame and one end of the truck bolster; and Fig. 4 is a vertical section taken on the line $a^4 a^4$ on Fig. 3.

The truck side frames 1 are, as shown, of the cast arch bar type, and at their central portions are provided with larger openings 2 in which are mounted the ends of a channel iron transom 3, the truck springs 4, the ends of the truck bolster 5, combined spring caps and roller bases 6 and lateral motion bearing rollers 7. The side frames 1, at the lower portions of the openings 2 have laterally extended flanges 8 affording bearings in the ends of the transom 3, and to which the said transom is rigidly secured by rivets 9. In line with the ends of the transom 3 and for a considerable distance above the same, the opening 2 is considerably wider than the said transom, but approximately, the upper half portion of the

said opening is preferably of about the same width as the said transom and is formed with wearing surfaces 10 with which the wearing surfaces 11 on the expanded ends of the bolster 5 are arranged to engage. Otherwise stated, the said wearing surfaces 10 are formed on those portions of the side frames which form the columns 10^a of said frames. The outer ends of the bolster 5 are preferably formed with projecting stop flanges or lugs 12 adapted to engage the outer sides of the column 10^a to limit the endwise movements of the bolster transversely of the truck. This bolster is adapted to be inserted endwise into working position, in respect to the side frames, before the transom or cross tie 3 has been applied, or when the said transom is removed from the lower portions of the openings 2 to afford the necessary clearance.

The truck springs 4, preferably arranged in a group of four, are seated directly on the ends of the transom 3 and indirectly on the bearing flanges 8 of said side frames. The combined spring cap and roller base 6 is supported by the springs 4 and have laterally spaced guide flanges 13 that embrace the upper portions of the bolster columns 10^a, and thereby guide the said element 6 for true vertical movements. The lateral motion rollers 7 are interposed between the combined spring cap and roller base 6, and the ends of the bolster 5, and engage suitable concave or dished seats in the said members 5 and 6, in the well known manner common in the commercial Barber trucks, whereby the bolster is yieldingly centered or held in an intermediate position. When the springs 4 are sufficiently compressed or removed, the combined spring cap and roller base 6 may be dropped down below the wearing surfaces 10 and removed by a horizontal edgewise movement out of the openings 2.

As the chief novel feature of this invention, I extend the wearing surfaces of the bolster columns by means of the brake hanger brackets which, in connection with cast side frames, are preferably cast integral therewith. In the drawings, these brake hanger brackets 14, which are cast integral with the side frames 1, have wearing surfaces 15 that are additional to and form continuations of the column wearing surfaces 10. The supplemental wearing sur-

face 15 nearly doubles the frictional surface engagement between the bolster and the truck side frames. This additional wearing surface is important with all truck bolsters having either vertical or endwise movements in respect to the side frames, but is especially important in connection with bolsters which have both of the said movements, with the resulting wear. The integral brake hanger brackets 14 have perforated lugs 16 to which the brake hanger links are adapted to be connected by a pin or bolt, not shown. By reference, particularly, to Fig. 3, it will be noted that the wearing surface on the ends of the bolster 5 are also increased longitudinally thereof, to give the required surface for engagement with the wearing surfaces 10 and 15.

In Fig. 1, the numeral 17 indicates the tie straps, the inner ends of which are secured by rivets 18 and dowel pins or studs 19, the lugs 20 being cast integral with the side frames 1. The dowel pins 19 are cast into the said lugs and engaged through perforations in the said straps. This affords a very simple and highly efficient means for connecting the tie straps to the side frames.

What I claim is:

1. A truck side frame having columns and

brake hanger brackets, both of which are provided with wearing surfaces for engagement with a bolster.

2. In a car truck, side frames and a truck bolster, said frames having columns and brake hanger brackets, both provided with wearing surfaces engageable with said bolster.

3. In a car truck, truck side frames and a bolster, said frames having columns and brake hanger brackets, both provided with wearing surfaces for engagement with said bolster and said bolster being spring supported in said side frames with freedom for vertical and endwise movements.

4. In a car truck, side frames having integral columns and brake hanger brackets, in combination with a truck bolster, a spring supported in said side frames, said columns and brackets both having wearing surfaces for engagement with said bolster.

In testimony whereof I affix my signature in presence of two witnesses.

JOHN C. BARBER.
